United States Patent Office

Des. 173,930
Patented Feb. 1, 1955

173,930

CHAIR OR THE LIKE

Theodore F. Belden, Idyllwild, Calif.

Application August 26, 1954, Serial No. 32,026

Term of patent 14 years

(Cl. D15—1)

Fig. 1.

Fig. 2.

To all whom it may concern:

Be it known that I, Theodore F. Belden, a citizen of the United States, a resident of Idyllwild, in the county of Riverside and State of California, have invented a new, original, and ornamental Design for a Chair or the like, of which the following is a specification, reference being had to the accompanying drawings, forming a part thereof.

Fig. 1 is a front perspective view of a chair or the like, showing my new design, and Fig. 2 is a rear perspective view thereof.

I claim:

The ornamental design for a chair or the like, as shown.
